John Enders

Inventor:

PHILIP S. MEDART,
by Robert Burns,
Atty.

UNITED STATES PATENT OFFICE.

PHILIP S. MEDART, OF ST. LOUIS, MISSOURI, ASSIGNOR TO FRED MEDART MANUFACTURING COMPANY, OF ST. LOUIS, MISSOURI, A CORPORATION OF MISSOURI.

BACK-STOP.

1,309,806.

Specification of Letters Patent. Patented July 15, 1919.

Application filed March 20, 1919. Serial No. 283,905.

To all whom it may concern:

Be it known that I, PHILIP S. MEDART, a citizen of the United States of America, and a resident of the city of St. Louis, State of Missouri, have invented certain new and useful Improvements in Back-Stops, of which the following is a specification.

This invention relates to a combined back stop and associated ball goal for basket ball games, and has for its object:

To provide a simple and efficient structural formation and combination of parts in a combined back stop and goal for the game of basket ball, adapted for ready and substantial connection with the stage of an assembly room and thus afford a convenient means for converting such assembly room into a play room for the game of basket ball, all as will hereinafter more fully appear.

20 In the accompanying drawing:

Figure 1, is a front elevation illustrating the association of the present invention with the elevated stage of an assembly room.

Fig. 2, is a side elevation of the same with 25 parts in section.

Fig. 3, is a plan view.

Like reference numerals indicate like parts in the several views.

Referring to the drawing, 1 designates the 30 usual elevated stage or platform of an assembly or like room with which the present improvement is associated.

2 designates a plurality of parts or uprights detachably secured to the floor of the 35 assembly room in adjacent relation to the front of the stage 1 by socket bushings 3 or other ordinary means of attachment.

4 designates a vertically disposed stop board or plate, preferably of a rectangular 40 shape, fixedly secured to the upper portions of the uprights 2, and a distance in front of the same by a plurality of approximately horizontal connecting rails or bars 5 as shown more particularly in Fig. 2.

45 6 designates a ball goal or basket of the ordinary form and construction secured in a depending manner from the central lower portion of the stop board 4 by the usual bracket frame 7 as shown in Figs. 1, 2 and 3.

50 8 designates a plurality of rearwardly extending inclined brace or stud members secured at their upper and forward ends to the uprights 2, and preferably between upper and lower pairs of the horizontal connecting rails 5 aforesaid. In the preferred

arrangement shown in Fig. 2, the lower and rear ends of the brace members 8 are detachably secured to the floor of the stage 1 by socket plates or bushings 9, or other ordinary means of attachment.

60

10 designates guy ropes or rods preferably extending from the rear portions of a lower pair of connecting rails 5 aforesaid, in lateral and oblique directions as shown in Figs. 1 and 2, with their lower ends detachably connected to the floor of the assembly room by screw-eyes or hooks 11, or like convenient attaching means.

65

12 designate turn-buckles forming a part of the aforesaid guy ropes 10, and adapted by their adjustment to tension said guy ropes in the operation of erecting and substantially securing the apparatus in place.

70

Having thus fully described my said invention what I claim as new and desire to 75 secure by Letters Patent, is:

1. In a basket ball back stop, the combination of a plurality of uprights adapted to engage in sockets in a floor, a stop board fixedly secured to the upper portions of said 80 uprights, inclined braces extending rearwardly from the upper portions of said uprights, and lateral guy members extending from the upper portions of said uprights to the floor of the room and provided with tensioning turn buckles, substantially as set forth.

85

2. In a basket ball back stop, the combination of a plurality of uprights adapted to engage in sockets in a floor, a stop board 90 fixedly secured in front of the upper portions of said uprights by approximately horizontal connecting rails, inclined braces extending rearwardly from the upper portions of said uprights, and lateral guy members 95 extending from the upper portions of said uprights to the floor of the room and provided with tensioning turn buckles, substantially as set forth.

95

3. In a basket ball back stop, the combination of a plurality of uprights adapted to engage in sockets in a floor, a stop board fixedly secured to the upper portions of said uprights, inclined braces extending rearwardly from the upper portions of said 100 uprights, a depending ball goal secured centrally to the lower portion of said stop board by a bracket frame, and lateral guy members extending from the upper portions of said uprights to the floor of the room and pro- 110

vided with tensioning turn buckles, substantially as set forth.

4. In a basket ball back stop, the combination of a plurality of uprights adapted to engage in sockets in a floor, a stop board fixedly secured in front of the upper portions of said uprights by approximately horizontal connecting rails, inclined braces extending rearwardly from the upper portions of said uprights, a depending ball goal secured centrally to the lower portion of said stop board by a bracket frame, and lateral guy members extending from the upper portions of said uprights to the floor of the room and provided with tensioning turn buckles, substantially as set forth.

5. In a basket ball back stop for the stage of an assembly room, the combination of a plurality of uprights adapted to rest in sockets in the floor of the room in adjacent relation to the stage thereof, a stop board fixedly secured to the upper portions of said uprights, rearwardly inclined braces extending from the upper portions of said up-

rights to the floor of said stage, and lateral guy members extending from the upper portions of said uprights to the floor of the assembly room and provided with tensioning means, substantially as set forth.

6. In a basket ball back stop for the stage of an assembly room, the combination of a plurality of uprights adapted to rest in sockets in the floor of the room in adjacent relation to the stage thereof, a stop board fixedly secured to the upper portions of said uprights, a depending ball goal secured centrally to the lower portion of said stop board by a bracket frame, inclined braces extending rearwardly from the upper portions of said uprights to the floor of said stage, and lateral guy members extending from the upper portions of said uprights to the floor of the assembly room and provided with tensioning means, substantially as set forth.

Signed at St. Louis, Mo., this 15th day of March, 1919.

PHILIP S. MEDART.
